WINDOW

Wilbur B. Burke, East Cleveland, Ohio

Application April 3, 1946, Serial No. 659,274

8 Claims. (Cl. 189—72)

1

Windows, as commonly constructed, have certain well-recognized handicaps. The sashes are unduly cumbersome and heavy. Their glass expanse transmits heat so freely that the addition of storm windows is resorted to in winter. They are awkward to clean on the outside unless a ladder be used, and in efforts at cleaning from the inside, not all of the glass can be effectively reached. In such efforts at double glazing as have been attempted, the attaining of a sufficiently tight seal to prevent moisture accumulation and condensation in the space between the glass has not been adequately successful. Added to this is the general tendency of sashes to stick or be moved with difficulty. In accordance with the present invention, however, construction may be had which obviates such difficulties; and desirably effective means of providing ample illumination without undue radiation losses, and with particular convenience of operation, may be provided. Other advantages in detail will be apparent from the following description.

To the accomplishment of the foregoing and related ends, the invention, then, comprises the features hereinafter fully described, and particularly pointed out in the claims, the following description and the annexed drawings setting forth in detail certain illustrative embodiments of the invention, these being indicative, however, of but a few of the various ways in which the principle of the invention may be employed.

In said annexed drawings:

Fig. 1 is an outside front elevational view of a window in accordance with the present invention;

Fig. 2 is a broken sectional view on enlarged scale, taken on a plane substantially indicated by line II—II, Fig. 1;

Fig. 3 is a fragmentary section on similar scale, taken on a plane substantially indicated by line III—III;

Fig. 4 is a fragmentary detail section taken on a plane substantially indicated by line IV—IV, Figs. 2 and 3;

Fig. 5 is a further enlarged fragmentary detail in transverse section showing the relationship of a glass pane and its receiving framing portion, prior to the seating of the pane in position, and Fig. 6 is a similar view with the pane in final position;

Fig. 7 is a fragmentary perspective view of the sash in relation to the sash-supporting framing, the parts being slightly spaced for clearer showing;

Fig. 8 is an inside elevational view of construction in accordance with the invention;

2

Fig. 9 is an enlarged fragmentary vertical section taken across the point of juxtaposition of the upper and lower sashes;

Fig. 10 is a fragmentary sectional view on enlarged scale, taken on a plane substantially indicated by line X—X, Fig. 8;

Fig. 11 is a transverse section on an enlarged scale, taken on a plane substantially indicated by line XI—XI, Fig. 8;

Fig. 12 is a fragmentary detail elevation of a corner joint of insert members shown in Fig. 11; and

Fig. 13 is a top plan view of the structure shown in Fig. 12.

Equipment in accordance with the present invention may be applied to new or old window frame openings. A sash guide 2, Fig. 3, is secured to the window frame 3 by suitable means, for example, by screws 4 passing through stops 5 and flanges 6 of the sash guide. Desirably, the sash guide 2 is made of metal, and sheet metal of suitable gauge can be stamped or rolled to provide the sash-guiding grooves. If the metal be of aluminum, brass, stainless steel or the like, freedom from corrosion or rusting is assured, and painting is also unnecessary on such parts. Desirably, the sash-guiding grooves in the sash-guide 2 may be made narrower than the thickness of the sash S, and may be relatively narrow grooves 8 to receive a corresponding tongue 9 projecting from the sash at its side or rail portions. If such tongue 9 be hollow, the space may be filled with a lubricant packing, as for instance wicking saturated with a suitable lubricant, and through holes 11, Fig. 4, at spaced intervals, feed of lubricant to the guideway may insure smooth operation in the sliding of the sash up and down.

The sash is formed of inner and outer channels 13, 14, secured together by suitable means, for instance spot welding, and the flanges 15, 16 are spaced sufficiently to receive the margin of the glass pane G. Preferably, the flanges 15, 16, are slightly resilient, and in the unglazed state may tend to close somewhat more closely than with the glass in place, and thus a uniformly close connection joint may be attained. Usually, a sealing means 18 is desirably also included, and while this may take the form of a rubber channel or the like embracing the edge of the glass pane, preferably I employ a sealing medium of plastic material which is initially fluent and can be injected into the space from the top after the glass is set in position, such plastic sealing material then subsequently setting to sufficient solidity to effectively seal the joint. Such material

may be of cementitious character thinned by a volatile solvent which evaporates, or more desirably it may be a thin synthetic resin which will set. The top edge of the sash is closed by the similar nested channels 13, 14, Fig. 4, fastened to the side or stile portions by angle brackets 19. It will be noticed that by the provision of the channel members 13, 14, as described, the flanges 15, 16, at each edge provide seating for double glazing, as shown most clearly in Figs. 2, 3 and 7, and the flanges being rebent toward each other thus hold the glass between opposed edge contacts or line contacts such as to preclude irregular warping and loosening. The glass may be set in position under conditions standardized to a minimum of moisture content for air included between the panes before they are sealed at the joints, or where desired, a vacuum may be provided between the panes. In either case, by reason of the efficient mount and sealing, a double-glazed structure may be free from excessive condensation which has been common in double-glazed sashes heretofore attempted.

As a further refinement, for rendering the sash particularly accessible for cleaning, the metal sash guide may be carried on hinges to allow swinging of the entire assembly into a position of easy accessibility for both sides of the glass. Thus, as illustrated in Fig. 11, the sash guide 2' may have a hinge mounting 22 along its edge, preferably piano-type hinges being used, and thereby the entire assembly can be swung inwardly, for instance, to allow convenient cleaning. To permit such swinging, the stops 5' are also hinged to swing out of the way, as indicated in dotted lines at the right end of Fig. 11. Also, sufficient clearance for the swinging of the rear edge of the sash guide may be assured by slightly cutting back the adjacent window frame, as at 23, Fig. 11. With this mounting, it is desirable to provide backing strips 24, of metal or wood, preferably wood, secured between the flanges of the sash guide 2' by suitable means, as screws 25; and the stiles and rails of such backing are preferably assembled such as to allow of slight adjustment for possible inequalities in the window frame opening being equipped. Thus, the joining corner ends of the stiles and rails, as shown at Figs. 12 and 13, may have saw-cuts 27, and flat L-shaped metal pieces 28 may be inserted therein, suitable screw fastenings or the like 29 being set through the wood and metal assembly with the desired dimensions as determined by the minor adjustment requisite to assure a proper fit. Desirably, a weather seal 30, Fig. 10, may be provided on the window sill 31, and if this be of slightly yieldable material, such as rubber, sponge rubber, and the like, particularly close fitting may be attained. A sheath 32 of sheet metal may be applied over the strip 30, affording protection and maintenance of its placement. If desired, the flange of the sheet metal sash guide or support 2' may be extended horizontally as at 33, so as to lap over the seal when the sash support with its included sashes is in its normal position, closed. On the top of the lower sash a weather seal 20 may be provided to cooperate with the upper sash. If desired, the bottom sheet metal sash guide or support may also have grooves 38' to receive a corresponding tongue 39' on the bottom of the lower sash.

Other modes of applying the principle of the invention may be employed, change being made as regards the detail described, provided the fea-

tures stated in any of the following claims, or the equivalent of such, be employed.

I therefore particularly point out and distinctly claim as my invention:

- 5 1. In window construction, a metal sash guide member, a double glazed sash member therein formed of nested sheet metal channels with the flanges of the inner channel spaced from the flanges of the outer channel to hold the edges of 10 glass panes therebetween, and inter-engaging means facilitating sliding movement of the sash member in the sash guide member including a longitudinal tongue formed in one member and a longitudinal groove formed in the adjacent portion of the other member.
- 15 2. In window construction, a double glazed sash formed of nested sheet metal channels with the flanges of the inner channel spaced from the flanges of the outer channel to hold the edges of 20 glass panes, said outer channel being shaped to form a longitudinally extending tongue projecting from each side portion of said sash, said mating flanges being further rebent toward each other to engage the glass between opposed edge contacts, and sealing material between the glass and the flanges.
- 25 3. In a window construction, a double glazed sash formed of nested sheet metal channels with the flanges of the inner channels spaced from the 30 flanges of the outer channels to hold the edges of glass panes, the outer channel being shaped to form a longitudinally extending tongue projecting from each side portion of said sash.
- 35 4. In a window construction, a double glazed sash formed of nested sheet metal channels with the flanges of the inner channels spaced from the flanges of the outer channels to hold the edges of 40 glass panes, and sealing material between the glass and the flanges, the outer channel being shaped to form a longitudinally extending hollow tongue projecting from each side portion of said sash, and apertures in said tongue.
- 45 5. In a window construction, a double glazed sash formed of nested sheet metal channels with the flanges of the inner channels spaced from the flanges of the outer channels to hold the edges of 50 glass panes, said channels including a longitudinally extending hollow tongue projecting from each side portion of said sash, apertures in said tongue, and lubricating means in said hollow tongue.
- 55 6. In a window construction, a sheet metal sash guide having longitudinal grooves, upper and lower sashes each comprising a double glazed sash formed of nested sheet metal channels with the flanges of the inner channel spaced from the flanges of the outer channel to hold the edges of 60 glass panes, and sealing material between the glass and the flanges, the outer channel being shaped to form a longitudinally extending tongue projecting from each side portion of said double glazed sash, said tongues each being slid able in one of said grooves in said sash guide.
- 65 7. In a window construction, a sheet metal sash guide having longitudinal grooves, upper and lower sashes each comprising a double glazed sash formed of nested sheet metal channels with the flanges of the inner channel spaced from the flanges of the outer channel to hold the edges of 70 glass panes, and sealing material between the glass and the flanges, the outer channel being shaped to form a longitudinally extending hollow tongue projecting from each side portion of said double glazed sash, said tongues each being

slidable in one of said grooves in said sash guide, and apertures in said tongues.

8. In a window construction, a sheet metal sash guide having longitudinal grooves, upper and lower sashes each comprising a double glazed sash formed of nested sheet metal channels with the flanges of the inner channel spaced from the flanges of the outer channel to hold the edges of glass panes, and sealing material between the glass and the flanges, said channels including a 10 longitudinally extending hollow tongue projecting from each side portion of said double glazed sash, said tongues each being slidable in one of said grooves in said sash guide, apertures in said tongues, and lubricating means in said hollow tongues.
